UNITED STATES PATENT OFFICE

JOHN J. CONWAY, OF BRIDGEPORT, CONNECTICUT, ASSIGNOR TO THE ACME SHEAR COMPANY, OF BRIDGEPORT, CONNECTICUT, A CORPORATION OF CONNECTICUT

SHIPPING AND DISPLAY CABINET FOR SHEARS

Application filed August 12, 1929. Serial No. 385,443.

This invention relates to a device for shipping and displaying shears or like articles, and has for an object to provide a display cabinet that may receive and display shears or like articles in an attention attracting manner, and to provide such a cabinet that may securely grip the contained articles yet permit them to be withdrawn without undue effort.

10 A further object of this invention is to provide a means for shipping the cabinet with the articles placed therein in display formation, whereby the storekeeper receiving the same need only remove the container used when shipping and the cabinet is ready with its articles in display formation to be placed on exhibition to the customers.

20 A still further object of this invention is to provide a closed display cabinet so constructed that the entire article may be displayed, and to provide a shelf therein having spaced openings in vertical alignment with correspondingly spaced openings in the cabinet top to receive the articles, to provide means in said openings to grip the sides of the articles and to provide recesses in the top openings to permit the passage of projections in the sides of the articles, such as the pivoting bolt or rivet in a pair of shears.

25 30 With the foregoing and other objects in view, this invention consists in certain combinations, constructions and arrangements of parts as set forth, disclosed and claimed in the following specification taken in consideration with the accompanying drawing.

In this drawing:

Fig. 1 is a front elevation of one embodiment of the display cabinet and contained articles therein placed in the opened shipping container, with the container cover broken away.

Fig. 2 is a partly broken section on line 2—2 of Fig. 1, the container being closed.

45 Fig. 3 is a section of the cabinet, per se

removed from the shipping container, the section being on line 3—3 of Fig. 4.

Fig. 4 is an enlarged fragmentary section of the cabinet top showing the spaced openings therein.

Fig. 5 is a fragmentary broken section on line 5—5 of Fig. 2, and

Fig. 6 is a perspective view of the cabinet in display position, a slightly different design of front panel being shown.

There is shown at 10 a closed display cabinet made of heavy paper, cardboard, pasteboard or the like material, the sides and edges being overlapped and pasted as at 11. Within the cabinet 10 and spaced between the top 12 and the bottom 13 is placed a transverse shelf 14 made of similar material, and it may be supported by legs 15 pasted to the inner sides of the cabinet. The cabinet as shown is used to hold and display shears 9 or scissors, but it will be understood that other similar articles could be so held and displayed, and as here shown, is of a size to display a dozen pairs of shears. Accordingly, a dozen spaced openings 16 are formed in the shelf 14 and a dozen correspondingly spaced openings 17 are formed in the cabinet top 12, the corresponding openings 16 and 17 being in vertical alignment. Each of the openings 16 and 17 are formed with short tongues 18 projecting from the ends and each pair of shears is intended to be inserted through a pair of vertically aligned openings 16 and 17 to thereby hold the shears in upright position when the cabinet stands on the lower end 13, the tongues 18 being bent downwardly as the shears are inserted, as shown in Fig. 5, to grip the edges of the shears and prevent them from shaking in the cabinet, or from getting loose when the cabinet and shears are being shipped.

If the tongues 18 are relatively short, they are stiffer and have a greater holding effect than when they are relatively long. It is to be understood that while the drawing shows a tongue at each end of the

openings, one tongue will be sufficient for holding the articles as shears in some cases, or it will in some cases be sufficient to have no tongues in either the upper or lower openings 5 and only one or two tongues in the other opening in which each article is inserted.

The sides of the openings 17 in top 12 are recessed as at 25 to permit the projecting heads of the pivoting rivet or screw 19 to pass 10 by into and out of the cabinet, no such recess being necessary in the opening 16 in shelf 14 because the rivet or screw 19 will come to rest above the shelf, as is apparent in Fig. 2.

When on display, the handles of the shears 15 will project above the top wall 12 of the cabinet and thus be visible to the prospective purchaser. To increase the display, the cabinet front 20 may have a design cut therein to permit the contained parts of the shears to be 20 visible. As shown in Fig. 1, the design may be cut into the shape of the contained articles, that is, a pair of shears, thereby serving to aid in catching the eye of the prospective purchaser, or as shown at 22, Fig. 6 however, 25 the design may be any other or fanciful design and preferably it should permit the blades to be visible, and especially the transverse shelf 14 and the openings therein to facilitate the insertion of the shears in the 30 cabinet.

In shipping, the cabinet 10 and the contained articles are intended to be enclosed in a carton or shipping box 23 having a folding cover or closure 24, which is of such size that 35 the cabinet and projecting handles will fit in the enclosing carton, as shown in Figs. 1 and 2. When in this carton, the shears will be held in place in the cabinet in display formation so that when the storekeeper receives 40 them, he has only to remove the cabinet from the carton, whereupon he may place the cabinet with the shears on display on his counter. It will also be noted from Fig. 2 that when the cabinet is in the shipping carton, the shears are each held firmly by the 45 walls 12 and 14 in spaced relation from the other shears so that they are effectively protected against breakage should they be subjected to rough handling. They are also 50 spaced from the side walls of the container insuring still further protection.

Thus it will be seen that this invention provides a novel means for displaying shears or like articles in an attractive manner and a 55 means whereby the cabinet may be safely shipped with the shears already placed therein in display formation and effectively protected against injury without the use of other packing means.

Having thus set forth and disclosed the invention, what is claimed is:

1. In a device of the character described for shipping and displaying shears, a closed cabinet open at the front, a shelf fixed in 65 said cabinet spaced below the top wall and

above the bottom wall, said top wall and shelf being provided with aligned substantially rectangular parallel spaced openings to position and display the shears with their handles in parallel planes, and short tongue means at the ends of said openings yieldable downwardly when shears are inserted in the openings to grip the edges of the shears to retain them against longitudinal movement. 70

2. In a device of the character described, a display cabinet for shears, a shelf in said cabinet, spaced below the top wall and above the bottom wall, the top wall and shelf being provided with a plurality of vertically aligned spaced substantially rectangular openings to receive the blades of the shears, short resilient tongues projecting from the ends of the openings yieldable downwardly when shears are inserted in the openings to grip the edges of the shears and retain them against longitudinal movement, the sides of the openings in the cabinet top being recessed between the tongues to permit the passage of projecting heads of the shear blade pivots. 80

3. In a device of the character described for shipping and displaying shears, a closed cabinet having a plurality of spaced substantially rectangular openings in its top wall, a shelf fixed in said cabinet between the top wall and bottom wall having spaced openings in alignment with the openings in said top to receive the blades of the shears to be displayed, and a resilient tab at one end of each opening in the top wall yieldable downwardly to grip one edge of the shears when the shears are inserted in the opening and retain them against upward displacement. 90

4. In a device of the character described for displaying and shipping shears, a closed cabinet having a top wall provided with a plurality of oblong openings arranged to receive the shanks of the shears and position and hold them so that the handles of the shears are displayed in substantially parallel relation and therefore are all visible from one side of the cabinet, and a shelf fixed in the cabinet between the top and bottom walls and having openings in alignment with the openings in the top wall to receive the blades of the shears and hold them in upright position, edges of the openings in one of said members being provided with resilient tabs yieldable downwardly when shears are inserted in the openings to grip the shears and hold them against upward displacement. 100

5. In a device of the character described for displaying and shipping shears, a cabinet having a plurality of spaced oblong openings in its top wall to receive and hold the shanks of the shears, said openings being arranged in substantially parallel relation so as to position the shears and display the handles in parallel relation so that they are all visible from one position, a resilient tab at one side of each opening yieldable downwardly to 110

grip the shears when they are inserted in the openings and retain them in the openings, and a shelf in said cabinet spaced below said top wall and above the bottom wall having a plurality of spaced openings, the openings in the shelf being in alignment with the openings in the top to receive the blades of the shears to be displayed and hold them in upright position.

10 In testimony whereof I affix my signature.
JOHN J. CONWAY.
